UNITED STATES PATENT OFFICE.

PHILIP L. RAYMOND, OF READING, PENNSYLVANIA.

SPARK-ARRESTER.

1,138,890.

Specification of Letters Patent.

Patented May 11, 1915.

Application filed June 23, 1914. Serial No. 846,732.

To all whom it may concern:

Be it known that I, PHILIP L. RAYMOND, a citizen of the United States, residing at Reading, in the county of Berks and State 5 of Pennsylvania, have invented certain new and useful Improvements in Spark-Arresters, of which the following is a specification.

My invention relates to improvements in spark arresters, the object of the invention being to provide a spark arrester which is adapted for use in connection with the modern type of locomotive smoke box, and which will cause the sparks to be broken up so that they cannot escape in any appreciable size 10 from the smoke stack.

A further object is to provide a spark arrester having its wall curved, and provide means for compelling the smoke and gases with their sparks to engage the curved surface 15 of the spark arrester, so that the sparks will be compelled to strike the wall at a tangent and be ground into a powder by such action.

A further object is to provide in a smoke 20 box an improved construction of table located between the exhaust nozzle at the lower end of the smoke box and the stack at the upper end of the smoke box, said table serving as a supporting means for a relatively 25 large screen connecting the smoke stack with the table, and said table also providing a means for connecting the upper end of a relatively small screen which is connected to and supported upon the steam nozzle, 30 it being understood, of course, that the table is provided with an opening registering with the screens so that there is a free passage 35 for smoke and gases and for steam from the nozzle to the stack.

40 A further object is to provide in the main or relatively large screen, an improved adjustable petticoat and mounting therefor, so that the petticoat may be adjusted vertically and its length varied to suit conditions.

45 A further object is to provide improvements of the character stated which facilitate the removal of the screen at any time desired, and which permit an inspection and repair of the boiler tubes after the screen has 50 been removed.

With these and other objects in view, the invention consists in certain novel features of construction, and combinations and arrangements of parts, as will be more fully 55 hereinafter described and pointed out in the claims.

In the accompanying drawings: Figure 1 is a view in longitudinal vertical section through the smoke box of an ordinary modern type of locomotive, showing my improvements in position therein. Fig. 2 is a view in section on the line 2—2 of Fig. 1. Fig. 3 is a view in horizontal section on the line 3—3 of Fig. 2. Fig. 4 is a top plan view of the smoke stack coupling ring. Fig. 5 is a 60 view in vertical transverse section through the main screen and the rings at the ends thereof. Figs. 6, 7, and 8, are plan views of the several rings forming a part of the main screen.

1 represents the forward end of a locomotive boiler having the ordinary tube sheet 3 located at the rear of the smoke box 4, and in which the tubes 5 are secured. This tube sheet 3 constitutes the rear wall of the smoke 65 box, and at the front end of said smoke box, the ordinary ring 6 is located with the head 7 secured thereto and provided with the ordinary door 8 through which access may be readily had to the interior of the smoke box 70 and the front end of the tubes.

On angle bars 9 secured to the sides of the smoke box, I secure and support my improved table 10 which extends horizontally and transversely throughout the smoke box 85 at the desired elevation. This table 10 consists of stationary end plates 11 and a removable center plate 12, the latter supported upon bars 13 secured below plates 11 and projecting inwardly from the inner end of 90 said plates and having openings to receive key bolts 14 which are positioned in recesses 15 in the edges of plate 12 and serve to securely hold the plate, yet allow the latter to be removed when desired.

The end plates 11, at their forward edges, are secured to an angle bar 16 which also supports the front edge of plate 12. The rear edges of plates 11 are secured to the lower end of a diaphragm 17, and the latter 100 is made up in section as will now be described.

To form the diaphragm, I provide end plates 18 which are connected by strips 19 and 20 at their upper and lower edges, so as 105 to provide an opening 21 through which access may be readily had to the boiler tubes or to the rear of the smoke box for purposes of inspection and repair. This opening 21 is normally closed by a removable door 22 110 which is provided in its ends with recesses 23 to receive key bolts 24 projected through the

plates 18 to hold the door in closed position and form a part of the diaphragm.

Handles 25 are provided on the door to facilitate its movement and access may be readily had to the same when the smoke box door 8 is open. The upper end of the diaphragm 17, comprising end plates 18 and strip 19, is secured to an angle bar 26 by key bolts 27.

10 The angle bar 26 is secured to the upper portion of the tube sheet 3 and extends transversely and horizontally across the rear end of the smoke box. The diaphragm is positioned at an incline as shown clearly in Fig. 1, and its lower end is bent and projected under the rear edge of the table 10. This lower end of the diaphragm consists of end plates 18 and strip 20, and is secured directly to the plates 11 and to the angle bars 9 at the sides of the smoke box.

15 It will be noted that the plates 11 are provided with recesses 28 for the accommodation of the steam pipes (not shown) which are adapted to be connected to the T-head or nigger head as it is known, which is located at the opening 29 in the upper portion of the tube sheet 3.

20 The table 10 supports my improved screen 30 which is of a wire mesh or other material having sufficiently small openings to prevent anything but relatively fine particles to pass therethrough. The wire mesh is a preferable construction because of its surface which grinds or grates the sparks into small

25 particles. The screen 30 is of general conical form throughout the greater portion of its circumference, but at the rear edge is preferably flattened as shown clearly in Fig. 3, so as to provide ample space at the rear for the accommodation of the nigger head and steam pipes.

30 The upper end of the screen 30 is provided with an angle ring 31 which is adapted to be secured by bolts 32 with a coupling ring 34. This coupling ring has a conical extension 35 adapted to project into the stack 36 and secured therein by bolts 37. The lower surface of the coupling ring 34 is in a horizontal plane so that the ring 31 may slide readily in a forward direction to permit the removal of the screen whenever desired.

35 The lower end of the screen is provided with a channel ring 38 rigidly secured to the wire mesh of the screen and located inside of a segmental clamping sleeve 39. This sleeve 39 is made preferably in two halves and is of a depth appreciably greater than the depth of the ring 38, so that the latter may be adjusted vertically in the sleeve 39, and when the proper adjustment is had, the sections of said sleeve 39 are secured together by clamping bolts 40. This adjustment at 40 the lower end of the basket permits the

screen to be utilized in various styles of locomotive where there will be but slight difference in the distance between the table and the stack.

45 After an adjustment is once had, it is to be understood there will be no further adjustment and the improvement is only for permitting the screen to have a slight variation in length to adapt it for the particular smoke box in which it is used.

50 A relatively small or auxiliary screen 41 connects the bottom of table 10 with the steam exhaust nozzle or pot 42. This screen 41 is preferably of cylindrical form with its angle ring 43 at the upper end bearing against the table and its angle ring 44 at its lower end secured to a collar 45 on the upper end of the nozzle or pot 42.

55 It is to be understood, of course, that the table has an opening 46, so that the exhaust steam has a free passage through both screens into the stack to induce the necessary draft.

60 At the front end of the table 10, I provide a deflector 49 which is connected by hinges 50 with end plates 11. This deflector consists of two plates 51 and 52, adjustable one upon the other to vary the length of the deflector. One of these plates is provided with a series of openings 53, and the other with a single opening 54 for the reception of bolts 55 to secure the plates at any position of adjustment.

65 The rear plate 51 is the one that is connected by hinges 50 to plates 11, and it will be observed that this plate at its upper portion throughout its length is bent at an angle, so that its downward and rearward movement is limited by contact with the angle bar 16.

70 To prevent the deflector from swinging upwardly by reason of vibration of the locomotive, I provide dogs 56 which are connected by hinges 57 to the lower edge of plate 52, and these dogs fall by gravity into position at an approximate perpendicular to plate 52 with their ends against the smoke box head 7, so that they serve as a positive lock. When it is desired, these dogs may be swung out of the way and the deflector plate raised to permit access to the smoke box below the table.

75 Inside of the screen 30, I provide a petticoat 47 which may have its length varied by adjusting a telescoping section 48 at its upper end. This section 48 is provided with a longitudinal series of openings 58, while the main portion 47 of the petticoat has a single opening 59 to receive a bolt 60 and secure the sections at any adjustment.

80 The petticoat as an entirety, is adjustable vertically in the screen. It is provided at opposite sides with metal straps 61 which have single openings 62 for the reception of bolts 63. These bolts 63 are adapted to be

projected through any of a series of openings 64 in metal bars 65 secured to the inner face of the screen.

It will be noted, particularly by reference to Fig. 5, that while these bars throughout the greater portion of their length, assume the angle of the wall of the screen, at a point between their ends they are bent so that they are located in a vertical plane parallel 10 to each other, and to the walls of the petticoat.

At the rear of the screen, I provide a bar 66, which has an off-set portion 67 against which the wall of the petticoat bears, but 15 the petticoat is not secured to this strap 66, and the latter serves merely as a guide for its vertical adjustment, and to hold it away from the wall of the screen.

The petticoat has a flared mouth 68 at its 20 lower end, so that the exhaust steam is directed centrally therethrough, and it will be noted, particularly by reference to Fig. 1, that the nozzle or pot 42, petticoat 47, and stack 35 are in direct alinement to induce 25 the desired draft.

The screen 30 is provided in its forward face with an opening 69 normally closed by a screen door 70, the structure being reinforced by metal frames 71 and 72 respectively around the opening 69 and door 70. These frames are secured together by bolts 73 which can be readily removed when access to the interior of the screen is desired.

In operation, the smoke and gases with 35 their sparks and cinders passing through the boiler tubes 5, are deflected downwardly under the table 10 by means of the diaphragm 17. A portion of the smoke and gases will enter the lower screen 41 and pass 40 up through the stack, but the greater portion will pass around the lower end of the deflector 49, and thence upwardly and rearwardly through the main screen 30 and through the stack.

45 It will be observed that with my improvements the sparks and the cinders can strike the screen at a tangent by reason of the shape of the screen, and by reason of the course which the products of combustion are compelled to take. When striking the screen at a tangent, the particles are broken, so that regardless of the draft, only the smallest particles can pass through the screen and out through the stack. With devices of this 50 kind, it is frequently desirable to remove the screen. The arrangement described facilitates this removal at any time without disturbing the other parts of the locomotive. The key bolts can be readily knocked out 55 even while hot, and the screen can be drawn out of the smoke box and cleaned or repaired. When the screen is withdrawn, the door 22 can be removed and access had to the boiler tubes. The center plate 12 of the 60 table 10 can be removed so that access may 65 be had to the lower portion of the smoke box.

While I have illustrated my improvements in connection with a particular type of smoke box with a particular type of locomotive front end, I would have it understood that by slight modification, the invention is adapted for use with practically all modern types of locomotive front ends, hence I do not limit myself to the precise 70 details set forth, but consider myself at liberty to make such changes and alterations as fairly fall within the spirit and scope of the appended claims.

Having thus described my invention, what 80 I claim as new and desire to secure by Letters Patent is:

1. In a spark arrester, the combination with a smoke box having a stack at its upper end, and an exhaust nozzle at its lower end 85 in line with the stack, of a support in the smoke box having an opening therein in line with the nozzle and the stack, a screen, a coupling ring secured on the upper end of the screen and having an upwardly projecting portion fitting within and secured to the stack, a sleeve adjustable vertically in the lower end of the screen and bearing directly upon the support, and a screen connecting the top of the nozzle with the support, substantially as described.

2. In a spark arrester, the combination with a smoke box having a stack at its upper end, and an exhaust nozzle at its lower end in line with the stack, of a support in the 100 smoke box having an opening therein in line with the nozzle and the stack, a screen, a coupling ring secured on the upper end of the screen and having an upwardly projecting portion fitting within and secured to the 105 stack, a segmental adjustable sleeve clamped around the lower end of the screen and bearing directly upon the support, and a screen connecting the top of the nozzle with the support, substantially as described.

3. In a spark arrester, the combination with a smoke box having a stack at its upper end, a horizontal table secured in the smoke box, a screen connecting the stack and the table, a ring fixed to the lower end of the 115 screen, and a sleeve adjustable on the ring and supporting the screen on the table, substantially as described.

4. In a spark arrester, the combination with a smoke box having a stack at its upper end, a horizontal table secured in the smoke box, a screen connecting the stack and the table, a ring secured to the lower end of the screen, and a segmental sleeve clamped around the ring and supporting the screen 120 upon the table, substantially as described.

5. In a spark arrester, the combination with a smoke box having a stack at its upper end, a horizontal table secured in the smoke box, a screen connecting the stack and the 130

table, a channel ring secured to the lower end of the screen, and a segmental sleeve clamped around the outer portion of said channel ring and supporting the screen upon 5 the table, substantially as described.

6. In a spark arrester, the combination with a smoke box having a stack at its upper end, a horizontal table secured in the smoke box, a screen connecting the stack and the 10 table, said screen having vertically adjustable securing means at its lower end adapted to support the screen upon the table, a coupling ring having an upwardly projecting portion located within and secured to the 15 stack, and said screen at its upper end having a ring adapted to be secured to said coupling ring, substantially as described.

7. In a spark arrester, the combination with a smoke box having a stack at its upper 20 end, a horizontal table secured in the smoke box, a screen connecting the stack and the table, a ring fixed to the lower end of the screen, a sleeve adjustable on the ring and supporting the screen on the table, a coupling 25 ring having an upwardly projecting portion located within and secured to the stack, and said screen at its upper end having a ring adapted to be secured to said coupling ring, substantially as described.

30 8. In a spark arrester, the combination with a smoke box having a stack at its upper end, a horizontal table secured in the smoke box, a screen connecting the stack and the table, a ring secured to the lower end of the 35 screen, a segmental sleeve clamped around the ring and supporting the screen upon the table, a coupling ring having an upwardly projecting portion located within and secured to the stack, and said screen at its 40 upper end having a ring adapted to be secured to said coupling ring, substantially as described.

45 9. In a spark arrester, the combination with a smoke box having a stack at its upper end, a horizontal table secured in the smoke box, a screen connecting the stack and the table, a channel ring secured to the lower end of the screen, a segmental sleeve clamped around the outer portion of said channel 50 ring and supporting the screen upon the table, a coupling ring having an upwardly projecting portion located within and secured to the stack, and said screen at its upper end having a ring adapted to be secured to said coupling ring, substantially as described.

55 10. In a spark arrester, the combination with a smoke box having a stack at its upper end, and an exhaust nozzle at its lower end in line with the stack, a horizontal table secured in the smoke box having an opening therein in line with the nozzle and the stack, a screen supported on the table and connected to the stack, said screen of 60 a general truncated conical form having a

flattened rear face, and a second screen connecting the bottom of the table with the nozzle, substantially as described.

11. In a spark arrester, the combination with a smoke box having a stack at its 70 upper end, and an exhaust nozzle at its lower end in line with the stack, of a horizontal table secured in the smoke box having an opening therein in line with the nozzle and stack, a screen, a coupling device at the upper end of the screen projecting into the stack, and a coupling device at the lower end of the screen adjustable vertically on the screen and securing the same to the table, substantially as described.

12. In a spark arrester, the combination with a smoke box having a stack at its upper end, and an exhaust nozzle at its lower end in line with the stack, of a horizontal table secured in the smoke box having an opening therein in line with the nozzle and stack, a screen, a coupling device at the upper end of the screen projecting into the stack, a coupling device at the lower end of the screen adjustable vertically on the screen 90 and securing the same to the table, said last-mentioned coupling device comprising a segmental ring, substantially as described.

13. In a spark arrester, the combination with a smoke box having a stack at its upper end, and an exhaust nozzle at its lower end in line with the stack, a horizontal table secured in the smoke box having an opening therein in line with the nozzle and the stack, a screen supported on the table and connected to the stack, bars secured inside the screen and having parallel vertical portions, said vertical portions having a series of openings therein, a petticoat in the screen, straps secured to the sides of the petticoat, and bolts projected through said straps and through any of said series of openings to secure the petticoat at various positions of adjustment, substantially as described.

14. In a spark arrester, the combination with a smoke box having a stack at its upper end, and an exhaust nozzle at its lower end in line with the stack, a horizontal table secured in the smoke box having an opening therein in line with the nozzle and the stack, a screen supported on the table and connected to the stack, three vertically positioned bars secured in the screen, all of said bars having off-set portions, a petticoat having means at opposite sides for attachment to two of said bars, and movable against the off-set portion of the third of said bars, substantially as described.

15. In a spark arrester, the combination with a smoke box having a stack at its upper end, and an exhaust nozzle at its lower end in line with the stack, of a horizontal table secured in the smoke box having an opening therein in line with the nozzle and stack, a screen, a coupling device at the up-

per end of the screen projecting into the stack, a coupling device at the lower end of the screen adjustable vertically on the screen and securing the same to the table, and a
5 second screen connecting the lower face of the table with the nozzle, substantially as described.

In testimony whereof I have signed my name to this specification in the presence of two subscribing witnesses.

PHILIP L. RAYMOND.
